Primary Examiner — Janice Patyk(74) *Attorney, Agent, or Firm* — Brinks Gilson & Lione(57) **CLAIM**

The ornamental design for a capsule, as shown and described.

DESCRIPTION

FIG. 1 is a top perspective view of a capsule, showing our new design;

FIG. 2 is a bottom plan view thereof;

FIG. 3 is a right side elevation view thereof;

FIG. 4 is a front elevation view thereof;

FIG. 5 is a left side elevation view thereof;

FIG. 6 is a rear elevation view thereof;

FIG. 7 is a top plan view thereof; and,

FIG. 8 is a cross-sectional view thereof, taken along line 8-8 of FIG. 2.
